UNITED STATES PATENT OFFICE.

PAUL WINSOR, OF WESTON, MASSACHUSETTS, ASSIGNOR TO THE UNION SWITCH AND SIGNAL COMPANY, OF SWISSVALE, PENNSYLVANIA, A CORPORATION OF PENNSYLVANIA.

SYSTEM OF SIGNALING.

No. 826,003.

Specification of Letters Patent.

Patented July 17, 1906.

Application filed January 27, 1902. Serial No. 91,332.

To all whom it may concern:

Be it known that I, PAUL WINSOR, a citizen of the United States, residing in Weston, in the county of Middlesex and State of Massachusetts, have invented an Improvement in Systems of Signaling, of which the following description, in connection with the accompanying drawings, is a specification, like letters and numerals on the drawings representing like parts.

This invention relates to a system of signaling especially designed and adapted for railroads, and is an improvement upon the block system of signals as now commonly used.

In the block-signaling system as now commonly employed and known to me the danger-signal for each block or section of the track is operated or controlled in its operation by an electromagnet or relay in circuit with the rails of the track comprising the section, which relay or magnet is normally energized by the signal-current when the track-section or block is clear, but which is short-circuited and designed to be deenergized when a locomotive or car is upon the track-section or block, which short circuit is designed to operate the signal and cause it to assume a position at "danger."

This invention has for its object to render the block system safe against false-signals due to currents other than the signal-currents, and for this purpose the signal relay or magnet in accordance with this invention is made responsive to the signal-currents flowing through the track-circuit, but is protected against and is irresponsive to extraneous currents which may pass through the track-circuit—such, for instance, as a trolley-current which may leak to the rails of a steam-railroad located in substantially close proximity thereto.

In the present embodiment of this invention the signal relay or magnet is responsive to a current rapidly varying in strength and of such a character as will affect the said magnet or relay through a transformer or a condenser, which latter instrumentalities safeguard the said relay or magnet from extraneous direct currents on the track-circuit.

These and other features of this invention will be pointed out in the claims at the end of the specification.

Figure 1 is a diagrammatic view of a suffi-

cient portion of a signaling system embodying this invention to enable it to be understood, and Fig. 2 a like view of a modification to be referred to.

Referring to Fig. 1, *a b* represent the rails of a track which is separated into blocks or sections by suitable insulation *c* in one of the rails, herein shown as the rail *b*. In the present instance the rail *b* is shown as separated into four sections 1 2 3 4, each of which may be of any desired length, and it will be understood that the rail *b* may be separated into any desired number of sections or blocks. Each block or track-section, as herein shown, is supplied with a normal signal-current from a transformer *d*, the primary coil *e* of which is connected by wires *f g* with the rail *a* and with a main-line conductor *h*, supplied with an alternating current from an alternating-current generator *i*, connected by wires *j k* with the conductor *h* and with the rail *a*. The secondary coil *m* of the transformer is connected to the rail *a* by wire *n* and to the section 2 of the rail *b*, near one end of said section, by wire *o*. The section 2 has connected to it near its other end by wire *p* one end of the primary coil *q* of a transformer *r*, the other end of which is connected by the wire *s* with the rail *a*. The secondary coil *t* of the transformer *r* is connected by wires *u v* in circuit with the signal magnet or relay *g*, which may be of any suitable construction and in the present instance is represented as provided with the armature *g*, pivoted at *h* and coöperating with a front stop *i*, the armature *g* being represented as acted upon by a retracting-spring *j*. As represented in Fig. 1, the track-section 2 is short-circuited by the wheels *l* and axle *m*, which may conventionally represent a locomotive or a car, and when the said section is thus short-circuited the current flows through the said wheels and axle and no longer flows through the primary coil *q* of the transformer *r*. Consequently the signal relay or magnet *g* is deenergized or weakened to such extent as to permit the armature *g* to be withdrawn by its spring *j*, thus placing the signal at "danger," which signal may be the armature itself, or, as is preferred, the armature opens a local circuit including the armature *g* and front stop *i* and a separate magnet, (not shown,) but which directly operates the sig-

nal, which may be of any usual construction such as a semaphore. As represented in Fig. 1, the track-section 3 is clear, and in this case the relay or magnet 9 is energized and its armature 10 is attracted, thus setting the signal at "safety." By reference to section 2 of the track it will be observed that when the said section is short-circuited as described any direct current which light flow through the track-circuit would not energize the signal magnet or relay 9, and consequently would not affect the signal or change its position from "danger" to "safety," as would be the case if the relay were energized by an extraneous direct current.

While I may prefer to use a transformer to safeguard the signal-relay from extraneous direct currents, I do not desire to limit my invention in this respect, as the same result may be accomplished by means of one or more condensers 22, as represented in Fig. 2, wherein the condenser is shown as included in circuit with the signal relay or magnet 9.

From the above description it will be seen that the alternating current employed on the track-circuit as the signal-current is of a different character from a continuous or direct current, such as is now commonly employed as the power-current on electric railways, and by the term "character" employed in the claims I desire to be understood as meaning some such difference as above pointed out and not a mere difference in the strength or in the direction of flow of a current of one kind or character.

I claim—

1. In a signaling system for railways, a track-circuit comprising a relay, a railway-signal controlled in its operations by said relay, a source of current-supply for said relay, and means which permit said relay responding to the current intended for it and which prevents said relay being affected to control the operations of said railway-signal by currents traversing said track-circuit of a different character.

2. In a signaling system for railways, a track-circuit comprising a source of current therefor which rapidly varies in strength, a relay responsive thereto, and means which permits said current to affect the relay and prevents any other currents traversing said track-circuit affecting the relay. 50

3. In a signaling system for railways, a track-circuit, comprising an alternating-current supply for said track-circuit, a relay in said track-circuit, and means which permits said alternating current to affect the relay and prevents direct currents traversing the track-circuit affecting said relay. 55

4. In a signaling system for railways, a track-circuit comprising a relay, a source of current-supply for affecting said relay to have it control one operation of a railway-signal, and means for preventing a different current traversing the track-circuit from affecting the relay. 65

5. In a signaling system of the class described, the combination with a track-circuit, of an alternating-current generator, a transformer having its primary coil in circuit with said generator and its secondary coil in said track-circuit, a second transformer having its primary coil in said track-circuit, and a signal magnet or relay in circuit with the secondary coil of said second transformer, substantially as described. 70

6. In a signaling system, the combination of a series of track signaling-circuits, a source of current from which each of said track signaling-circuits are supplied, a relay device for each track signaling-circuit, and means in each track signaling-circuit for preventing a different current traversing the track-circuit from operating the translating device. 80

In testimony whereof I have signed my name to this specification in the presence of two subscribing witnesses.

PAUL WINSOR.
